(57) **CLAIM**

The ornamental design for a makeup mirror as shown and described.

DESCRIPTION

FIG. 1 is a front, left perspective view of a makeup mirror showing my new design;

FIG. 2 is a rear, right, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, left perspective view of the makeup mirror, shown in a closed configuration;

FIG. 10 is an enlarged view of portion 10 shown in FIG. 2; and,

FIG. 11 is an enlarged view of portion 11 shown in FIG. 5. The dash-dot broken lines in the drawings depict portions of the makeup mirror that form no part of the claimed design.

The dot-dash broken lines represent boundaries of the enlarged portions and form no part of the claimed design.

1 Claim, 11 Drawing Sheets
